UNITED STATES PATENT OFFICE

2,112,867

LOOM TEMPLE

Robert Stevenson, Providence, R. I., assignor to
Mechanical Holding Corporation, a corporation
of Rhode Island

Application September 27, 1935, Serial No. 42,473

6 Claims. (Cl. 139—295)

This invention relates to a loom temple for holding woven fabric taut in a widthwise direction in a loom, and has for one of its objects the provision of a loom temple which will be 5 adapted for use with fabrics of varying thicknesses without manual adjustment.

Another object of the invention is the provision of a construction of loom temple which will operate upon fabrics of varying thicknesses with 10 substantially the same amount of frictional engagement regardless of the thickness of the cloth.

Another object of the invention is the elimination 15 of markings on light weight, fragile goods such as silk or rayon by the use of toothed rolls as occurs in the old style temple.

Another object of the invention is the provision of a loom temple the parts of which will need to be replaced less frequently than temples which have heretofore been in commercial use.

With these and other objects in view, the invention consists of certain novel features of construction, as will be more fully described, and particularly pointed out in the appended claims.

In the accompanying drawing:

Fig. 1 is a perspective view of the loom temple and its mounting structure;

Fig. 2 is a top plan view of the device with the cap and movable carriage removed and showing the base with spaced rolls mounted therein;

Fig. 3 is a perspective view of the movable carriage;

Fig. 4 is a plan view of the underside of this carriage;

Fig. 5 is a perspective view of the cap or guide member;

Fig. 6 is a perspective view of the resilient member or spring;

Fig. 7 is a sectional view through the central portion of the device; and

Fig. 8 is a sectional view on line 8—8 of Figure 7.

In the use of loom temples it is usually required that adjustments be made when varying thicknesses of fabrics are woven in the loom. In 45 the Gilpin Patent No. 1,934,495, dated Nov. 7, 1933, with which I am familiar, an attempt has been made to provide an easy adjustment of a bar in the temple, but no adjustment occurs automatically nor is there any adjustment of the 50 fabric engaging guiding edges, so that different surface frictions occur depending upon the thickness of the cloth woven in the loom; and in order to provide a device in which there will be substantially the same sinuous path provided 55 through the temple and one in which the adjustments need not be made mechanically, I have provided a carriage for mounting a roll above the spaced base rolls so that the entire carriage with the roll is movable up and down and spring 60 pressed toward the base, the edge of the carriage

serving as the guides for the fabric to determine its path of travel over the base rolls; and the following is a more detailed description of the present embodiment of this invention, illustrating the preferred means by which these advantageous results may be accomplished:

With reference to the drawing, 10 designates the base of the loom temple which is provided with spaced bearings 11 and 12 at one end and 13 and 14 at the other end for rotatably mounting in spaced relation the axles of the rolls 15 and 16. This base is provided with a suitable arm 17 having a lip 19 with holes 20. A bracket 18 adjustably receives the arm 17 for supporting the same in position on the loom. One end of the base is provided with a groove 22 which receives the tongue 23 of the cap and guide member 24 which has overhanging arms 25 of generally L-shaped cross-section with an elongated opening 26 between them and, as shown in Fig. 5, is of generally rectangular form with a bridge piece 27 connecting the arms 25 at their outer ends, said arms and bridge piece overhanging the base and being spaced therefrom.

A carriage 30 is mounted for vertical movement in the opening or space 26 between the arms 25, this carriage being provided with guide surfaces 31 to engage the inner surfaces 32 of the arms 25 on either side thereof, and a guide surface 33 on the upstanding portion 34 to engage the inner surface 35 of the bridge piece 27 at one end and a guide surface 36 at the other end to engage the inner surface 37 between the arms 25 at the other end. Thus, this carriage is guided and may move vertically between the inner edges 32 of the arms 25 and the inner surface 35 of the bar 27 and the inner surface 37 of the body portion of this cap. The lower portion of the carriage below the surfaces 31 broadens to provide abutment surfaces 38 located beneath the arms 25, while the edges of the lower surface of the carriage are provided with lips 39 which are rounded to provide guide surfaces for the cloth 40 in passing from between the rolls. Resilient means such as a leaf spring 41 are located 45 beneath each of the arms 25 to engage the surfaces 38 of the carriage to tend to force it downwardly. A groove 42 is provided on the underside of this carriage in which there is mounted a roll 43 in bearings 44 at either end thereof to 50 be moved with the carriage toward the rolls on the base.

In operation, the woven fabric passes over the spaced rolls 15 and 16 and beneath the edges 39 and the upper roll 43, as shown in Figure 7. The thicker the fabric the more the carriage will be forced up against the tension of the springs 41, while the fabric will maintain substantially the same sinuous path and the same extent of frictional contact with the rolls regardless of its 60

thickness. Further, by reason of this loom temple no mechanical adjustments such as shimming up the cap or attempting to adjust screws or bolts or the like is necessary each time a different thickness fabric is operated on by the loom.

The foregoing description is directed solely towards the construction illustrated, but I desire it to be understood that I reserve the privilege of resorting to all the mechanical changes to which the device is susceptible, the invention being defined and limited only by the terms of the appended claims.

I claim:

1. In a loom temple, a base, spaced cloth engaging members rotatably mounted on said base, a cap supported by said base and having an extended portion overhanging the base and spaced therefrom, said overhanging portion being provided with a longitudinally extending opening therethrough, a carriage movably positioned above said base for vertical movement in said opening in said cap, said carriage being provided with guide surfaces to slidably engage the adjacent wall surfaces of said opening and be guided thereby during any up and down movement of the carriage with respect to said cap, a cloth engaging member rotatably mounted in said carriage and located partly between and above said spaced base rolls, and spring means for bodily moving the entire carriage with its cloth engaging member toward said base.

2. In a loom temple, a base, spaced cloth engaging rolls rotatably mounted thereby, a cap supported by said base and having an extended portion overhanging the base and spaced therefrom, said overhanging portion being provided with a longitudinally extending opening therethrough, a carriage movably supported above said base for vertical movement in said opening in the cap, said carriage being provided with guide surfaces at its sides and ends to slidably engage the adjacent wall surfaces of said opening and be guided thereby during vertical movement of the carriage, a cloth engaging roll rotatably mounted in said carriage and located partly between and above said spaced base rolls, and spring means for bodily moving the entire carriage with the roll carried thereby towards the rolls on said base.

3. In a loom temple, a base, spaced cloth engaging rolls rotatably mounted thereby, a cap supported by and in fixed spaced overhanging relation to said base, said overhanging portion of said cap being provided with an elongated opening therethrough of generally rectangular shape and extending longitudinally thereof for substantially the major portion of its length, a carriage movably supported above said base and shaped to fit within said opening in said cap for vertical sliding movement therein and be guided by engagement with adjacent wall surfaces of said opening, cloth engaging lips on said carriage located on opposite distant sides of said rolls, a rotatable cloth engaging roll mounted in said carriage and located partly between and above said spaced base rolls, and resilient means acting between said cap and carriage for moving the entire carriage with its roll towards the rolls in said base.

4. In a loom temple, a base, spaced rolls rotatably mounted thereby, a cap supported by and in fixed spaced relation to said base, said cap being provided with a portion overhanging the base having an elongated opening therethrough and

extending longitudinally thereof to form spaced overhanging side arms, a carriage movably supported for vertical movement above said base, said carriage having a narrow upper portion movably positioned in said opening of said cap and provided with guide surfaces to slidably engage the adjacent inner surfaces of said arms and end walls of said opening and be guided thereby during any up and down movement of the carriage with respect to said cap, the lower portion of said carriage below the guide surfaces thereof being wider than said opening to provide a laterally extending abutment surface located beneath each of said side arms, a roll rotatably mounted in said carriage and located partly between and above said spaced base rolls, and a spring located beneath each of said side arms to engage the undersurface of an arm and an abutment surface of the carriage for moving the entire carriage with its roll towards the rolls on the base.

5. In a loom temple, a base, spaced rolls rotatably mounted thereby, a cap supported by and in fixed spaced relation to said base, said cap being provided with a portion overhanging the base having an elongated opening therethrough and extending longitudinally thereof to form spaced overhanging side arms of generally L-shaped cross-section with inwardly facing recesses, a carriage movably supported for vertical movement above said base, said carriage having a narrow upper portion movably positioned in said opening in said cap and provided with a wider lower portion extending laterally thereof to provide an abutment surface located beneath each of said side arms, a roll rotatably mounted in said carriage and located partly between and above said spaced base rolls, and a spring located beneath each of said side arms and in each of said recesses to engage the undersurface of an arm and an abutment surface of the carriage for moving the entire carriage with its roll towards the rolls on the base.

6. In a loom temple, a base, spaced rolls rotatably mounted thereby, a cap supported by and in fixed spaced relation to said base, said cap being provided with a portion overhanging the base having an elongated opening therethrough of generally rectangular shape and extending longitudinally thereof to form spaced overhanging side arms of generally L-shaped cross-section with inwardly facing recesses, a carriage movably supported for vertical movement above said base, said carriage having a narrow upper portion movably positioned in said opening in said cap and provided with guide surfaces to slidably engage the adjacent inner surfaces of said arms and end walls of said opening and be guided thereby during any up and down movement of the carriage with respect to said cap, the lower portion of said carriage below the guide surfaces thereof being wider than said opening to provide a laterally extending abutment surface located beneath each of said side arms, a roll rotatably mounted in said carriage and located partly between and above said spaced base rolls, and a spring located beneath each of said side arms and in each of said recesses to engage the undersurface of an arm and an abutment surface of the carriage for moving the entire carriage with its roll towards the rolls on the base.
